UNITED STATES PATENT OFFICE.

CHARLOTTE E. GALLEY, OF BUFFALO, NEW YORK.

RUBBER-CUSHIONED HORSESHOE.

SPECIFICATION forming part of Letters Patent No. 634,410, dated October 3, 1899.

Application filed February 9, 1899. Serial No. 705,053. (No model.)

To all whom it may concern:

Be it known that I, CHARLOTTE E. GALLEY, a citizen of the United States, residing at Buffalo, in the county of Erie and State of New York, have invented a new and useful Rubber-Cushioned Horseshoe, of which the following is a specification.

The invention relates to improvements in rubber-cushioned horseshoes.

Heretofore metal horseshoes have been provided with rubber cushions; but in order to effect a secure connection between the same and the shoes it has been necessary to employ a rubber cushion of a thickness which will not admit of frog-pressure and which is exceedingly expensive. It has also been found by experience that with these shoes a considerable amount of rubber has to be discarded after the cushion has worn down to the fastening devices, owing to the fact that the latter are located at a point between the upper and lower faces of the cushion and must be placed a considerable distance from the upper or inner face of the cushion in order to secure the necessary stability.

The object of the present invention is to improve the construction for attaching rubber cushions to metal horseshoes and to enable the fastening devices to be located at the upper or inner face of the cushion in order to enable practically the entire cushion to be worn away before discarding it.

A further object of the invention is to enable cushions of less thickness than those heretofore used to be employed, thereby greatly lessening the cost of the same and at the same time permitting frog-pressure.

The invention consists in the construction and novel combination and arrangement of parts hereinafter fully described, illustrated in the accompanying drawings, and pointed out in the claims hereto appended.

In the drawings, Figure 1 is a perspective view of a horseshoe constructed in accordance with this invention, the cushion being removed. Fig. 2 is a perspective view of the cushion. Fig. 3 is a detail sectional view taken longitudinally of one side. Fig. 4 is a detail sectional view of the front of the horse-shoe. Fig. 5 is a detail sectional view on line 5 of Fig. 4. Figs. 6 and 7 are detail views of the front and rear anchoring devices.

Like numerals of reference designate corresponding parts in all the figures of the drawings.

1 designates a horseshoe provided at its inner and outer edges with longitudinal flanges 2 and 3, forming walls and providing a longitudinal groove or channel for the reception of a continuous rubber cushion 4, conforming to the configuration of the horseshoe and adapted to be readily interlocked with the same after the said horseshoe has been secured to the hoof of an animal. The horseshoe is provided at opposite sides with cross-pieces 5 and 6, preferably formed integral with the side walls, as illustrated in the accompanying drawings, and located at points near the center and rear ends of the sides of the horseshoe. These rigid cross-pieces are engaged by substantially L-shaped anchors or tongues 7 and 8, located at the upper or inner face of the cushion and adapted to be interlocked with the cross-pieces 5 and 6 by sliding the sides of the cushion in the grooves or channels of the sides of the horseshoe. By locating the anchors or tongues 7 and 8 at the upper or inner face of the cushion the entire body of the latter lies beyond the cross-pieces 5 and 6, as clearly illustrated in Fig. 2 of the accompanying drawings, so that practically the entire cushion may be worn before it has to be discarded. Also this arrangement enables a cushion of much less thickness to be employed than can be when the fastening devices pass through the body portion of it, and by decreasing the thickness of the cushion the expense is greatly reduced and frog-pressure is permitted.

The rear anchors or tongues are constructed of sheet metal or other suitable material, and each pair consists of a single strip of metal having its end portions bent to form similarly-disposed L-shaped arms, and the intermediate connecting portion 9, which is disposed parallel with the cushion, is embedded in the same and is provided with openings 10, adapted to cause the rubber lying above and below the connecting portion 9 to be united at intervals, as clearly shown in the drawings. In practice the longitudinal portions of the tongues or anchors 7 and 8 will lie close to the inner or upper face of the cushion, and the latter will fit against the

face of the horseshoe; but in Figs. 2 and 3 the construction is exaggerated in order to illustrate it more clearly.

The nail-holes 11 of the horseshoe are arranged between the walls 2 and 3, and after the shoe is attached to a hoof in the usual manner the sides of the cushion are introduced between the walls, and by sliding them rearward the anchors or tongues will engage the cross-pieces. The front portion of the cushion is then forced in position and may be secured by any suitable means, such as transverse pins 12, passing through perforations 13 and 14 of the inner and outer walls 2 and 3 and engaging loops or bends of a front anchor 15, constructed of a strip of sheet metal similar to the rear anchors. The front anchor, which is curved to conform to the configuration of the front of the horseshoe, is provided equidistant of its ends with transverse bends 16, forming inwardly or upwardly offset eyes, located adjacent to the upper or inner face of the cushion and receiving the fastening devices. The front anchor is provided with openings 17, formed at intervals to permit the rubber above and below the metal to be united similar to that heretofore described. The anchors are molded in the cushion and the rubber is then vulcanized, and by constructing the anchors of sheet metal or similar material they are resilient, and when the cushion wears down to the fastening devices its resiliency will not be lessened.

35 The invention has the following advantages: The means for attaching the cushion to the metal shoe are simple and comparatively inexpensive in construction. They possess strength, durability, and resiliency, and they are located at the inner or upper face of the cushion, so that the entire body portion of the same will lie beyond the cross-pieces 5 and 6, thereby greatly lessening the thickness of the cushion. By reducing the thickness of the rubber cushion the cost of construction is greatly lessened and frog-pressure is permitted.

Changes in the form, proportion, size, and the minor details of construction within the scope of the appended claims may be resorted to without departing from the spirit or sacrificing any of the advantages of this invention.

What is claimed is—

55 1. In a device of the class described, the combination with a horseshoe, of a cushion arranged thereon, and locking devices carried by the cushion and engaging the shoe, said locking devices being located at the inner or upper face of the cushion and terminating short of the lower or outer face of the same, substantially as described.

2. In a device of the class described, the combination with a horseshoe having a groove or channel and provided with cross-pieces spanning the same, of a cushion arranged

within the groove or channel and provided at its inner or upper face with tongues or anchors detachably interlocked with the cross-pieces, substantially as described.

70

3. A device of the class described comprising a horseshoe having a groove or channel and provided at opposite sides with cross-pieces, a cushion fitting in the groove or channel, and the anchors mounted on the cushion and provided at the inner or upper face thereof with longitudinal tongues detachably interlocked with the cross-pieces, substantially as described.

75

4. A device of the class described comprising a horseshoe provided with a groove or channel and having cross-pieces, a cushion, and the anchors consisting of strips of metal embedded in the cushion and having externally-arranged tongues detachably interlocked with the cross-pieces, substantially as described.

80

5. A device of the class described comprising a cushion provided at its inner or upper face with anchors or tongues, and a horseshoe provided with devices arranged to be engaged by the anchors or tongues, whereby the cushion is interlocked with the shoe, substantially as described.

85

6. A device of the class described comprising a shoe having inner and outer walls and provided at opposite sides with cross-pieces, a continuous cushion provided at opposite sides with anchors for engaging the cross-pieces, said cushion being provided at its front with an anchor forming an eye, and a fastening device engaging the eye and the shoe, substantially as described.

90

7. A device of the class described comprising a shoe, a cushion, a front anchor consisting of a strip of metal embedded in the cushion and provided with bends forming eyes, fastening devices engaging the eyes and the shoe, and means for securing the sides of the cushion to the shoe, substantially as described.

105

8. A device of the class described comprising a shoe provided with inner and outer walls, a continuous cushion fitting between the walls and provided at its inner or upper face with anchors interlocked with the shoe at opposite sides thereof, and means for securing the front of the cushion to the shoe, substantially as described.

110

9. A device of the class described comprising a horseshoe, a cushion arranged thereon and having an unbroken outer face, and devices located at the inner face of the cushion and detachably connecting the same with the horseshoe, substantially as described.

120

In testimony that I claim the foregoing as my own I have hereto affixed my signature in the presence of two witnesses.

CHARLOTTE E. GALLEY.
